UNITED STATES PATENT OFFICE.

FRANK THAYER, OF CALLERY, PENNSYLVANIA.

WRENCH.

1,085,644.

Specification of Letters Patent.

Patented Feb. 3, 1914.

Application filed May 7, 1913. Serial No. 766,123.

To all whom it may concern:

Be it known that I, FRANK THAYER, a citizen of the United States of America, residing at Callery, in the county of Butler 5 and State of Pennsylvania, have invented certain new and useful Improvements in Wrenches, of which the following is a specification, reference being had therein to the accompanying drawing.

10 This invention relates to wrenches, and more particularly to a quick acting structure that can be used in connection with monkey, bicycle, nut and other types of wrenches.

The primary object of my invention is to 15 provide simple and effective means in connection with the adjustable jaw of the wrench, whereby the jaw can be rapidly shifted and at the same time permit of a minute adjustment being obtained when 20 occasion so requires.

Another object of this invention is to provide a nut and rack wrench wherein novel 25 means is employed for holding the nut normally in engagement with the rack of the wrench, whereby the adjustable jaw will be held against accidental displacement.

A further object of this invention is to 30 provide a wrench of the above type consisting of comparatively few parts that are inexpensive to manufacture, easy to assemble, and highly efficient for the purposes for which they are intended.

With the above and other objects in view 35 the invention resides in the novel construction, combination and arrangement of parts to be hereinafter specifically described and then claimed.

Reference will now be had to the drawing, wherein:—

40 Figure 1 is a side elevation of a wrench in accordance with this invention, Fig. 2 is a similar view partly broken away and partly in section, and Fig. 3 is a cross sectional view of the wrench.

45 A wrench in accordance with this invention comprises a flat shank 1 having the outer end thereof provided with an integral or fixed jaw 2 that presents a flat gripping surface 3 at right angles to the front side of the shank 1. The front side of the shank 1 is provided with a rack 4 having concave 50 equally spaced ratchet teeth.

55 Slidably mounted upon the shank 1 is an adjustable jaw body 5 having a longitudinal opening 6 to receive the shank 1. The jaw body 5 has a jaw 7 presenting a flat gripping

surface 8 that confronts and cooperates with the flat gripping surface 3 of the jaw 2 in gripping the facets of a nut. The jaw body 5 has a transverse slot 9 and arranged longitudinally of said slot and screwed into the body 5 is a screw 10. Loosely mounted upon the screw 10 within the slot 9 is a nut 11 that has a longitudinal opening 12 of greater diameter than the screw 10, whereby the 60 nut will be loosely held within the slot 9 by said screw. The nut 11 has the periphery thereof provided with spiral teeth 13 adapted to mesh with the rack 4 of the shank 1. The nut also has an annular groove 14 and 70 extending into said groove and embracing approximately one-half of the nut is a yoke 15 provided with a stem 16. The stem 16 is supported by a casing 17 arranged at the front side of the jaw body 5, said casing having one end thereof secured to the jaw 7 by a screw 18 or other fastening means, while the opposite end of the casing extends under the inner end of the jaw body and is held by the screw 10. Encircling the stem 16, between the casing 17 and the yoke 15 is a 80 coiled compression spring 19 that holds the yoke 15 normally in the groove 14 and the nut 11 normally in engagement with the shank 1. 85

To rapidly adjust the jaw body 5, the nut 11 is gripped between the fingers and pulled outwardly, that is, toward the casing 17, and the adjustable jaw body can then be rapidly shifted longitudinally of the shank 90 1. By releasing the nut the coiled spring 19 places the same in engagement with the shank and then the nut can be rotated to minutely adjust the jaw body 5 relatively to said shank.

95 The wrench in its entirety is made of light and durable metal, and while in the drawing, there is illustrated a preferred embodiment of the invention, it is to be understood that the structural elements are susceptible to such variations and modifications as fall within the scope of the appended claim.

What I claim is:—

In a wrench, the combination with a shank having a fixed jaw and a rack in the front 105 side thereof, of an adjustable jaw body slidably mounted upon said shank and having a jaw confronting the jaw of said shank, said adjustable jaw body having a transverse slot formed therein, a screw arranged longitudinally of said slot, a nut loosely mounted in said slot and retained therein by said screw 110

and adapted to engage the rack of said shank, said nut having an annular groove formed therein, a casing having one end thereof held by said screw and the opposite end thereof secured to the jaw of said jaw bdy, a yoke engaging in the groove of said nut and having a stem extending into said casing, and a coiled compression spring encircling the stem of said yoke for holding

said yoke in engagement with said nut and to said nut normally in engagement with the rack of said shank.

In testimony whereof I affix my signature in the presence of two witnesses.

FRANK THAYER.
